US00D967177S

(12) **United States Design Patent** (10) Patent No.: **US D967,177 S**
(45) Date of Patent: **** Oct. 18, 2022**

(54) **DISPLAY SCREEN OR PORTION THEREOF
WITH GRAPHICAL USER INTERFACE**

(71) Applicant: **Apple Inc.**, Cupertino, CA (US)

(72) Inventors: **Patrick Lee Coffman**, San Francisco, CA (US); **Raymond Sepulveda**, Portland, OR (US)

(73) Assignee: **Apple Inc.**, Cupertino, CA (US)

(**) Term: **15 Years**

(21) Appl. No.: **29/819,659**

(22) Filed: **Dec. 16, 2021**

Related U.S. Application Data

(63) Continuation of application No. 29/800,034, filed on Jul. 19, 2021, now Pat. No. Des. 941,346, which is a

(57) **CLAIM**

The ornamental design for a display screen or portion thereof with graphical user interface, as shown and described.

DESCRIPTION

The file of this patent contains at least one drawing/photograph executed in color. Copies of this patent with color drawings(s)/photograph(s) will be provided by the Office upon request and payment of the necessary fee.

The sole FIGURE is a display screen or portion thereof with graphical user interface showing our new design.

The peripheral dashed broken lines illustrate a display screen or portion thereof, and form no part of the claimed design.
